HOOP-ROLLING STICK OR SIMILAR ARTICLE

Thomas M. Chrisco, Fresno, Calif.

Application November 17, 1952, Serial No. 22,328

Term of patent 14 years

(Cl. D34—5)

To all whom it may concern:

Be it known that I, Thomas M. Chrisco, a citizen of the United States, residing at 711 North Fulton Street, Fresno, county of Fresno, and State of California, have invented a new, original, and ornamental Design for a Hoop-Rolling Stick or Similar Article, of which the following is a specification, reference being had to the accompanying drawing, forming a part hereof.

Fig. 1 is a perspective of a hoop-rolling stick or similar article, showing my new design.

Fig. 2 is a side elevation of the device shown in Fig. 1.

Fig. 3 is a front elevation of the device.

Fig. 4 is a transverse section taken through a handle portion of the device on line 4—4 in Fig. 1.

I claim:

The ornamental design for a hoop-rolling stick or similar article, as shown.

THOMAS M. CHRISCO.
